UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS. A CORPORATION OF MASSACHUSETTS.

DRILL-TOOL.

1,293,081.

Specification of Letters Patent.

Patented Feb. 4, 1919.

Application filed January 17, 1908. Serial No. 411,209.

To all whom it may concern:

Be it known that I, GEORGE H. GILMAN, a citizen of the United States, residing at Claremont, in the county of Sullivan, State 5 of New Hampshire, have invented an Improvement in Drill-Tools, of which the following description, in connection with the accompanying drawings, is a specification, like letters on the drawings representing 10 like parts.

My invention relates to rock drills, being more particularly concerned with means for clearing the drill hole during cutting by means of water or pressure fluid or both.

15 My invention will be best understood by reference to the following description when taken in connection with the accompanying illustration of one specific embodiment thereof, while its scope will be more particularly pointed out in the appended claims.

In the drawings:—

Figure 1 shows one form of pneumatic drill, partly in section, to which one embodiment of my invention is shown applied; 25 Fig. 2 is a detail of the cut-off valve shown in the tool of Fig. 1 for cutting off the connection between the exhaust passages at opposite ends of the cylinder;

Fig. 3 is a detail in section showing a 30 portion of the invention relating to the holding chuck for the drill bit; and,

Fig. 4 is a section in detail showing a modified construction of the tool shown in Fig. 1.

35 Referring to the drawings and particularly to the embodiment of my invention there shown, Fig. 1 shows one form of the same applied to a construction of hammer or impact drill tool, which is shown for 40 illustrative purposes as of a usual and well-known type, except for features to be herein more specifically referred to. It is to be understood that my invention is applicable to hammer drills and tools of other constructions than the one herein shown, the 45 particular one illustrated being submitted for the sole purpose of disclosing one concrete embodiment of my present invention. Referring, however, to the details of the 50 illustrated form of tool, the same is provided with a cylindrical or barrel portion 1, carrying at one end the grasping portion or handle 2, herein secured to the cylinder through the medium of the intermediate

valve block 3, the cylinder portion having 55 at the opposite end the chuck 4 fixedly held within the end of the cylinder portion and acting as a holder for the shank 5 of the cutting tool or drill bit 6. The shank portion of the drill bit is provided with 60 means, such as its hexagonal cross-section shape herein shown, to prevent relative rotative movement between the bit and the chuck, while permitting the slight necessary endwise movement between the two. 65

In the specific type of tool illustrated there is provided within the cylinder 1 the striking member 7, having reciprocatory movement therein and adapted at each stroke to strike an impact receiving portion, 70 herein (Fig. 1) the head end of the drill bit shank 5. As illustrated, this striking member is in the form of a hammer piston, to the opposite ends of which the pressure fluid is alternately admitted and from which 75 it is alternately exhausted, the control thereof residing in a differentially operated valve 8, as is common in this class of tools, although for purposes of the broad aspects 80 of my invention the particular construction of the valve, or the presence or absence of a valve separate from the piston, is immaterial.

In the particular tool shown, pressure fluid is admitted to the hammer through the 85 pressure supply pipe 9 connected to the base portion 10 of the handle, thence passing through suitable passages (not herein necessary to show) to the valve chamber. The valve controls the admission of such pressure fluid to the head end 11 of the cylinder, whence it is exhausted by passages (also 90 not herein necessary to show) which communicate with one or more radial exhaust passages 12, the latter connecting with the 95 annular groove 13, from which the exhaust may be permitted to escape to the atmosphere through the adjustable valve 14.

Pressure fluid is admitted at the appropriate time to the lower end of the cylinder 100 under control of the valve 8 through the admission passage 15, the exhaust being permitted to escape into an exhaust chamber 16 when the reduced end of the hammer piston withdraws on its upward stroke 105 from the reduced portion 17 of the cylinder barrel which intervenes between the exhaust chamber and the cylinder.

The pressure fluid supply pipe 9 leads to a suitable source of compressed air or other pressure fluid, and there is also provided a supply pipe 18 leading to a suitable 5 source, preferably of water, the latter maintained under any desired or suitable head or pressure. The water supply may be controlled through any appropriate device, such as the controlling valve 19, and is 10 connected to the elbow 20, the latter threaded into the walls of the cylinder and having free communication with the exhaust chamber 16, so that a constant and easily 15 controllable supply of water may be admitted to the exhaust chamber.

While any appropriate impact receiving block or part may rest upon the end of the drill shank to receive the blow of the piston, in the present instance the shank of the drill 20 bit itself extends into the exhaust chamber and constitutes such impact receiving part to receive the blow of the hammer piston and is provided with an axially arranged bore or passage 21 extending through the entire 25 length of the drill bit, through which passage the combined exhaust pressure fluid and water is adapted freely to escape, thereby clearing the drill hole of chippings and dust.

To prevent the possible leakage of water 30 from the exhaust chamber 16, except through the central bore of the drill bit, any suitable means may be provided, but herein an effective device for this purpose is secured by the provision of the annular packing washer 22 35 of rubber or other suitable packing material interposed between the enlarged portion 23 of the drill bit and the mouth or face of the chuck 4.

It will be observed that the elbow 20 provides a fixed water attachment for the cylinder which, if desired, may be taper-threaded 40 into the cylinder so that leakage is entirely avoided.

Although free access of the water to such 45 space as is employed to receive the exhaust, may be prevented by the provision of a suitable means if desired, preferably, as in the illustrated embodiment of my invention, the water has free access to an exhaust space, 50 such as the space 16, from which it is readily expelled through the longitudinal bit passage 21. The repeated discharge of the expanding pressure fluid to the exhaust space 16 recurs so rapidly that the chamber 55 is kept quite clear and the commingled air and water is caused to pass out of the space through the passage 21 in a continuous stream, and as rapidly as it can enter the same, without the least interference (as practice has demonstrated) with the efficient operation of the hammer piston.

Since exhaust occurs before completion of the up-piston stroke, the down stroke of the piston is preceded by the expansive discharge 60 of the exhaust pressure fluid from the

forward end of the piston into the chamber 16. Such previous expansive discharge of fluid, which fluid must escape through the longitudinal bit passage, positively prevents any possible tendency of the water to follow 70 the piston on its up stroke and impede the down-stroke thereof.

One advantage of great practical importance consequent upon the employment of a hammer drill constructed as shown, is the 75 possibility of using the exhaust pressure fluid to assist in discharging the water while introducing the latter longitudinally through the drill bit or other impact receiving parts without weakening the latter 80 through the provision of a lateral supply passage or passages formed in the impact receiving parts. Such lateral introduction of the water also avoids trouble from the possible longitudinal displacement of the 85 supposedly alining passages in the impact receiving parts and the walls of the cylinder or other surrounding portion of the drill tool.

While I have described in connection with 90 Fig. 1 the shank 5 of the bit as constituting the impact receiving part which projects into the exhaust space 16 to receive the blow of the piston and conduct the water therefrom, I recognize no distinction, so far as the 95 broad aspects of my invention are concerned, where separate and additional impact receiving members are employed to rest upon the end of the drill shank and communicate thereto the blow of the hammer piston. 100

In Fig. 4 I have shown the drill shank 5 surmounted by the impact receiving block 35, the same being provided with a longitudinal passage 24 alining with the drill bit passage 21 and opening communication between the same and the space beneath the hammer portion 7 of the piston. The drill shank being herein shown as of uniform cross-section, the block 35 will be normally 105 pressed against the upper walls of the chamber 16, and there is provided means, such as a plurality of edge grooves 25 in the block, permitting the free access of water from the chamber 16 to the space above the impact block so as to permit its ready escape through 110 the passage 24, means, such as the packing ring 23*, being also employed to prevent the passage of water down the sides of the block. 115

In the employment of the hammer drill described, the quantity of water passed 120 through the drill bit may be regulated as desired. If desired, the water supply may be entirely cut off by means of the valve 19, or the water connections may be entirely removed from the tool, and the exhaust 125 alone employed to clear the drill hole. In the event that the water supply is dispensed with, the exhaust from the lower end of the piston may be augmented by leading also to the exhaust space 16 the exhaust pressure 130

fluid discharge from the opposite end of the cylinder through the radial passages 12.

For this purpose there is provided a passage 26 connecting the exhaust space 16 with the exhaust passages 12 leading from the head end of the cylinder. Where the tool is to be employed at times in connection with the water supply referred to and at other times without the same, this passage is preferably provided with suitable means which may be employed to open or close at will communication between the exhaust passage leading to the opposite ends of the cylinder, so that such communication may be closed when the water supply is utilized and opened when such supply is cut off. I have shown herein, for this purpose, a valve in the form of a transversely apertured plug 27 connected to an externally exposed head 28 by which the same may be placed in the position shown in Fig. 1, cutting off communication between opposite ends of the passage 26, or in the position shown in Fig. 2, where such communication is opened. The plug 27 is slidably seated within the threaded thimble 29 in the bottom of which it is normally seated by the spring 30. A pin 31 secured transversely through the stem of the plug is adapted to seat in either one of two sets of right-angle grooves formed in the head of the thimble. The plug may therefore be withdrawn and turned to either of the positions shown, but when seated by its spring the pin 31 prevents its accidental displacement.

Where the exhaust discharge alone is employed, the plug valve 27 is arranged as shown in Fig. 2, permitting the exhaust from both ends of the cylinder to pass into the space 16 and through the drill bit passage 21. The escape cock 14 provides an auxiliary exhaust outlet to the atmosphere which may be more or less open or entirely closed, as conditions may require a lesser or greater discharge of the exhaust pressure fluid through the drill bit. If the tool is to be again used with the water supply described, the plug valve 27 may be set in the position shown in Fig. 1 and the exhaust cock 14 opened wide.

Referring to Figs. 1 and 3, the drill chuck 4 is preferably held fixed in position by the pin or key 32 extending transversely through the surrounding cylinder portion 56 and also through a groove or cutaway part of the bushing. In order to lock or retain this key in position, the ends of the same are preferably held and protected by some means such, for example, as the encircling retaining ring 33, which is seated in an appropriately shaped groove in the outer walls of the surrounding portion of the cylinder. Such retaining ring is preferably elastic and split, as at 34, so the same may be readily removed for the withdrawal of the pin when

the removal of the bushing is desired. This permits the bushing readily to be withdrawn without dismantling the tool, while, on the other hand, no accidental displacement of the bushing is permitted.

70

While I have referred to various advantages which are consequent upon the use of the preferred construction of tool by which I have illustrated my invention, and while other advantages will be obvious to those skilled in the art, my invention is not limited to the particular tool construction disclosed nor to such constructions as necessarily possess all the advantages of the one disclosed, but on the contrary comprehends extensive modifications and departures from the disclosed form thereof as well as the utilization of the various features of novelty, as pointed out by the appended claims, severally and each without reference to the absence or presence of the various other features of novelty residing in the said invention.

80

Claims:

1. A pressure fluid hammer drill having a hammer piston adapted to reciprocate therein, a drill bit presenting a suitable impact receiving part to receive the blow of the hammer, said drill bit having a longitudinal exit passage extending to the cutting end, said drill having an exhaust space having open communication with the longitudinal passage in the bit, to which space the pressure fluid is intermittently exhausted from the cylinder, and means also for admitting water to the exhaust space.

90

2. A pressure fluid hammer drill having a drill bit presenting an impact receiving part, a hammer piston to strike the same, said bit being provided with an open passage extending from the cutting end thereof through the impact receiving part, said drill having a chamber communicating with the open end of the impact receiving part, and means for introducing pressure fluid exhaust and water to said chamber for exit through said passage.

95

3. A hammer drill having a reciprocating hammer piston, a drill bit provided with a longitudinal water passage leading to the cutting end, said bit presenting a suitable impact receiving part to the blow of the hammer piston, said hammer drill being provided with a chamber in which the impact-receiving end of said part is exposed, which chamber communicates with the said longitudinal passage, and means for introducing water into said chamber.

105

4. A pressure fluid hammer drill having a hammer piston, a drill bit provided with a longitudinal passage leading to the cutting end, said drill having a chamber through which the hammer piston reciprocates, an impact receiving portion exposed to the blow of said piston within said chamber, means

110

115

120

125

130

for supplying water to said chamber, and means also for supplying pressure fluid thereto.

5. A pressure fluid hammer drill having a hammer piston, a drill bit provided with a longitudinal water passage leading to the cutting edge, an impact-receiving part adapted to receive the hammer blow and communicate the same to the cutting edge 10 of the tool, said drill being provided with a chamber within which the impact-receiving end of said part is exposed, said chamber communicating with said longitudinal drill bit passage, means for supplying water 15 to said chamber, and means also for supplying pressure fluid exhaust thereto.

6. A pressure fluid hammer drill having a hammer piston, a drill bit, the latter having a longitudinal passage leading to its 20 cutting edge, said drill having an exhaust chamber adapted to be intermittently placed in communication with one of the cylinder ends, and means for supplying water to the drill bit passage by way of the said exhaust 25 chamber.

7. A hammer drill having a reciprocating hammer piston provided with a striking end, said drill having a chamber in which the striking end thereof operates and separated 30 from the cylinder by a passage which said striking end enters and withdraws from, means for intermittently opening the same directly to the forward end of the cylinder to permit the escape of fluid pressure 35 exhaust thereto, and a drill bit having a combined pressure fluid and water exit passage leading to the cutting end, said passage having communication with the said chamber.

8. A hammer drill having a hammer piston 40 provided with a striking end, said drill having a chamber within which the striking end is adapted to operate, said chamber being separate from the cylinder thereof, means for intermittently opening said chamber to the cylinder to permit the escape of pressure fluid exhaust thereto, means for supplying water to said chamber, a drill bit having a combined water and pressure fluid exhaust exit passage leading to the 50 cutting end and communicating with said chamber, and means for supplying water through said chamber to said passage.

9. A hammer drill having a hammer piston, a hollow drill bit, means for supplying 55 water to said drill bit, and means for causing pressure fluid exhaust to be supplied thereto during the backward stroke of the piston and during the first part of the forward stroke thereof.

60 10. A hammer drill having a hammer piston, a hollow drill bit, means for supplying water thereto, said drill having an exhaust space communicating with the hollow interior of said drill bit, and means for supplying pressure fluid exhaust to the exhaust

space during the backward movement of the piston.

11. A hammer drill having a reciprocating hammer piston, a hollow drill bit, said drill having an exhaust space adapted to 70 receive intermittently the pressure fluid exhaust on the backward movement of the piston, means for supplying water to the hollow drill bit, and means for forcibly expelling the same through admission of pressure fluid thereto from the exhaust space. 75

12. A hammer drill having a hammer piston and provided with a chamber in which the forward end of the latter is adapted to move, a drill bit having a longitudinal passage leading to the cutting end thereof and having communication with said chamber, means for supplying water to said chamber, and means for causing the expulsion thereof through said passage with the assistance of 85 exhaust pressure fluid from the said hammer drill.

13. A hammer drill having a hammer piston and provided with a chamber in which the forward end of said hammer is adapted to move, a drill bit having a longitudinal passage leading to the cutting end thereof and provided at the opposite end with an impact-receiving part through which the said passage extends into the said chamber, 95 means for admitting water to said chamber, and means for expelling the same through said passage by means of exhaust pressure fluid from the hammer drill. 90

14. A hammer drill having a hammer piston and provided with a chamber in which the forward end of said piston is adapted to move, a drill bit having a longitudinal passage leading to the cutting end thereof and having communication with said chamber, 105 means for supplying water to said passage, and means for expelling the same through said passage by means of exhaust pressure fluid discharged from the forward end of the piston. 100

15. A hammer drill having a hammer piston, and provided with an exhaust space to which exhaust pressure fluid is admitted on rearward movement of the piston, a drill bit having a longitudinal passage leading to the 115 cutting end, and means for supplying water to said passage, there being provided communication between the supplied water and the exhaust space whereby the exhaust pressure fluid assists in expelling the water 120 through said passage. 110

16. A pressure fluid hammer drill having a hammer piston, a drill bit presenting a suitable impact-receiving part to the blow of the piston, there being provided a longitudinal valveless passage extending through said drill bit and impact-receiving part from end to end, a chamber with which the inner end of said passage directly communicates, and means for expelling commingled pres- 125 130

- sure fluid and water through said chamber and passage.
17. A hammer drill having a hammer piston, a drill bit, said bit having a water passage leading to the cutting end thereof, means for supplying water to said passage, and means for expelling the same there-through through the assistance of the hammer piston's pressure fluid exhaust, said water supply having free access to the space surrounding the striking end of said piston.
18. In a pneumatic percussive drill, a cylinder, a piston, a hollow drill steel actuated by said piston, passages for conveying fluid from both ends of said cylinder to the bore of said steel, and means for throttling the exhaust of the drill.
19. The combination in a pneumatic tool, of means for the passage of fluid from the rear of the working piston directly to the bore of a hollow drill or cutter carried by the tool for the purpose of removing debris from the working face, and means for throttling the exhaust from the tool for the control of the operation of the tool and of the flow of fluid for the removal of the debris from the working face, substantially as described.
20. A pneumatic tool comprising a cylinder having ports for the admission and exhaust of fluid, a piston within said cylinder, a hollow drill or cutter carried by the cylinder, means for the direct passage of fluid from the rear of the piston to the bore of the hollow drill or cutter, means for the control of the admission and exhaust of fluid to and from the fore and rear ends of the piston, and means for throttling the exhaust from the tool substantially as described.
21. A hammer drill having a hammer piston from the opposite ends of which pressure fluid is alternately exhausted, a drill bit provided with a longitudinal discharge passage leading to the cutting end, and means for discharging the combined exhaust from both ends of said piston through said drill bit.
22. A hammer drill having a hammer piston from the opposite ends of which pressure fluid is alternately exhausted, said drill having a passage leading to the atmosphere through which said pressure fluid exhaust may escape, a drill bit, the latter provided with an exit passage leading to the cutting end of said drill bit, and means also permitting the escape of the combined pressure fluid exhaust from both ends of said piston through said drill bit.
23. A hammer drill having a hammer piston from the opposite ends of which pressure fluid is alternately exhausted, a drill bit having an exit passage leading to the cutting end thereof, means permitting the escape of the combined exhaust pressure fluid from both ends of said piston through said drill bit, said drill having an auxiliary exhaust opening leading directly to the atmosphere, and means for varying more or less the effective area of said auxiliary exhaust opening.
24. A hammer drill having a hammer piston from the opposite ends of which pressure fluid is alternately exhausted, and means for cutting off or establishing communication at will between the exhaust passages leading to the opposite ends of said piston.
25. A drill tool having a working cylinder, means for admitting pressure to and exhausting the same from the opposite ends of said cylinder alternately to cause the actuation of the tool, and means for cutting off or establishing communication at will between the exhaust passages leading to the opposite ends of said cylinder.
26. A rock drill having a working cylinder from the opposite ends of which pressure fluid is alternately exhausted, a drill bit having an interior passage, means for supplying water to the cutting end of said drill bit through the said passage, means for cutting off said water supply at will, means for supplying pressure fluid exhaust from one end of said cylinder through said passage, and means for opening or closing communication between the exhaust passages leading to the opposite ends of said cylinder, said drill having an auxiliary exhaust passage leading to the atmosphere.
27. A hammer drill having a reciprocating hammer piston, a drill bit provided with a longitudinal water passage leading to the cutting end, said bit presenting a suitable impact-receiving part to the blow of the hammer piston, said hammer drill being provided with a chamber in which the impact-receiving end of said part is exposed, which chamber communicates with the said longitudinal passage, and means for introducing water into said chamber about the rear end of said impact-receiving portion.
28. A hammer drill having a hammer piston, a hollow drill-bit, means for supplying water to said drill-bit, and means under the control of said piston for causing exhaust pressure fluid to be supplied thereto during the backward stroke of the piston, and during the first part of the forward stroke thereof.
29. In a drilling machine, the combination with a fluid actuated motor and a drill bit associated therewith, the latter having a passage way therein, of means for delivering exhaust fluid from one end of the motor to the drill bit, and means for preventing the passage of the actuating fluid from the other end of the motor to the drill bit and thereafter delivering the same as exhaust fluid thereto.
30. In a drilling machine, the combination of the combined exhaust pressure fluid

- tion with a fluid actuated motor and a drill bit associated therewith, the latter having a passageway therein, of means for delivering exhaust fluid from one end of the motor to 5 the drill bit, means for preventing the passage of the actuating fluid from the other end of the motor to the drill bit and thereafter delivering the same as exhaust fluid thereto, and means for controlling the flow 10 of exhaust fluid to said bit.
31. A hammer drill having a hammer piston from the opposite ends of which pressure fluid is alternately exhausted, said drill having a passage leading to the atmosphere 15 through which said pressure fluid exhaust may escape, a drill bit, the latter provided with an exit passage leading to the cutting end thereof, and means for controlling the supply of exhaust fluid either to the atmosphere 20 or to the exit passage in said bit.
32. A hammer drill having a hammer piston to the opposite ends of which pressure fluid is alternately supplied, said drill having a passage leading to the atmosphere, a 25 drill bit, the latter provided with an exit passage leading to the cutting end thereof, and means for proportioning the flow of the pressure fluid through said passage leading to the atmosphere and through the passage 30 in said bit to the cutting end thereof.
33. A hammer drill having a hammer piston from the opposite ends of which pressure fluid is alternately exhausted, said drill having an exhaust passage leading to the 35 atmosphere, a drill bit, the latter provided with an exit passage leading to the cutting
- end thereof, and means for proportioning the flow of the exhaust pressure fluid through said exhaust passage leading to the atmosphere and through said exit passage in said 40 bit.
34. A hammer drill having a hammer piston from the opposite ends of which pressure fluid is alternately exhausted, said drill having a passage leading to the atmosphere through which said pressure fluid exhaust may escape, a drill bit, the latter provided with an exit passage leading to the cutting end thereof, and means including a throttle valve for varying the proportion of the exhaust fluid flowing to the atmosphere and to said bit. 45
35. In a drilling machine, the combination with a fluid actuated motor and a drill bit associated therewith, the latter having a 50 passageway therein, of means for delivering exhaust fluid through the motor to the drill bit, means for preventing the passage of the actuating fluid from the motor to the drill bit, and means other than the first 55 delivering means having communication with the drill bit for supplying other cleansing fluid to the same in advance of said preventing means.
- In testimony whereof, I have signed my 60 name to this specification, in the presence of two subscribing witnesses.
